H. F. WOERNLEY

AUTOMATIC CAR COUPLER

Filed July 10, 1924

INVENTOR
HARRY F. WOERNLEY
BY *John M. Bady*
ATTORNEY

UNITED STATES PATENT OFFICE.

HARRY F. WOERNLEY, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC CAR COUPLER.

Application filed July 10, 1924. Serial No. 725,264.

This invention relates to automatic car and air line couplers of the tight lock type provided with a locking lever or latch which is adapted to engage a surface on a counter-
5 part coupling head in order to lock the heads together.

The principal object of my invention is to provide means for positively locking the locking lever or latch in its coupler locking
10 position.

In the accompanying drawing; Fig. 1 is a side elevation of an automatic coupler head with my improvement applied thereto; Fig. 2 a plan view thereof, partially in section; and Fig. 3 a partial plan view thereof, showing the means for securing the locking pin to the coupler head.

As shown in the drawing, the coupler head 1 is provided with projections 2 adapted to interlock with corresponding projections of a counterpart coupler head. The coupler heads are locked together in the coupled position by means of a pivoted latch 3, having a cam face 4 adapted to engage a surface 5 of the counterpart coupler head. The latch 3 is operated by a rod 6, which is pivotally connected to the latch and is subject to the pressure of a coil spring 7 tending to force the latch 3 into its locking
25 position.

A double fork member 8 is secured to the end of the rod 6, the prongs of which straddle a cam 9 and intermediate the two pairs of prongs, a roller 10 is pivotally mounted so as to be engaged by the projections 11 of the cam 9 when the cam is rotated. Said cam is secured to a pin 12 which is adapted to be rotated by a handle 13 secured to the pin.

According to my invention, a locking pin 40 14 is provided for positively locking the latch 3 in its coupler locking position. The curved extensions 15 of the latch 3, which straddle the rod 6 and are pivotally connected to the rod by pin 16, are extended, 45 as shown in the drawing, Fig. 2, and are provided with recesses to receive the locking pin 14. The coupler head is provided with lugs 17 having apertures for receiving the pin 14.

In operation, when a pair of coupler heads have been coupled, the locking pin 14 is inserted in the apertures of the lugs 17, so that the pin engages the recesses of the extensions 15 and thereby positively locks the 55 latch 3 against movement from its coupler locking position.

When the pins 14 are withdrawn to permit unlocking of the coupler heads, by operation of the handle 13, each pin is retained 60 with the coupler head by means of a chain 18, secured to the coupler head.

Having now described my invention, what I claim as new and desire to secure by Letters Patent, is:—

In an automatic car coupler, the combination with a coupler head having a rigid knuckle and a latch for engaging a counterpart coupler head to thereby lock the counterpart knuckles together, of lugs carried 70 by said head and having apertures disposed in the path of said latch and a pin manually insertable in said openings to engage said latch and thereby prevent movement thereof from its locked position.

In testimony whereof I have hereunto set my hand.

HARRY F. WOERNLEY.
